DESIGN FOR A TOY PISTOL

Russell Abner Frisbie, Middletown, Conn., assignor to The J. & E. Stevens Company, Cromwell, Conn., a corporation

Application June 8, 1934, Serial No. 52,107

Term of patent 7 years

To all whom it may concern:

Be it known that I, RUSSELL ABNER FRISBIE, a citizen of the United States, residing at Middletown, in the county of Middlesex and State of Connecticut, have invented a new, original, and ornamental Design for a Toy Pistol, of which the following is a specification, reference being had to the accompanying drawing, forming a part thereof.

Figure 1 is a side elevation of a toy pistol, illustrating my new design.

Fig. 2 is a plan view of the same.

Fig. 3 is an end elevation of the same.

Fig. 4 is a side elevation showing the side opposite to that of Fig. 1.

The dominant feature of the design consists in the particular configuration of the moving or rotating portion of the cylinder.

I claim:

The ornamental design for a toy pistol, as shown and described.

RUSSELL ABNER FRISBIE.
